R. F. WILLIAMS

GLARE SHIELD

Filed July 9, 1925

Reaf F. Williams
By Hugh K. Wagner,
Attorney

UNITED STATES PATENT OFFICE.

REAF F. WILLIAMS, OF ST. LOUIS, MISSOURI.

GLARE SHIELD.

Application filed July 9, 1925. Serial No. 42,441.

This invention relates to glare shields, and more specifically to a means embodying a pane for shielding the eyes of the operator of a motor-vehicle from glare such, for instance, as that of wet sunlit pavements, expanses of snow, and the blinding headlights of other vehicles looming up before him and proceeding in the opposite direction.

One of the objects of the invention is to provide a device for this purpose which may be readily attached with a minimum of time and trouble to any common type of automobile windshield.

Another object is to provide a glare shield which may be easily adjusted by the operator to accommodate the position thereof to his visual comfort and needs, without unduly obscuring his view through the windshield.

A further object is the provision of means whereby the glare-shielding pane, such as a strip of colored celluloid, may be readily detached from the other parts thereof without removing screws or having to manipulate other awkward and inconvenient fastening devices commonly employed in devices of this character.

Other objects and advantages will appear in the course of the following description of the preferred embodiment of this invention.

In the accompanying drawings forming part of this specification, in which like numbers of reference denotes like parts wherever they occur,

Figure 1 is a front elevation of the device;

Figure 2 is an end view;

Figure 3 is a fragmentary sectional view taken on the line 3—3 in Figure 2;

Figures 4 and 5 are respective views of the individual members comprising the means for fastening the pane to the operating means of the device;

Figure 6 is a fragmentary view of a pane as it appears detached; and

Figure 7 is a fragmentary view of a modification especially applicable to limousines rather than to the windshields of open cars.

The illustrated embodiment of the invention comprises a glare-softening pane, preferably in the form of a sheet of darkened or suitably colored transparent celluloid 1, in the present instance green, having near each end thereof a pair of juxtaposed slits 2, through which pass the tongues 3, formed

as narrowed continuations of the ends 4 of a U-shaped band 5, whereby the ends 4 form shoulders which react against one side 6 of the glare-subduing pane 1. The tongues 3 have transverse openings or recesses 7 therein, for pivotally receiving the laterally extending end portion 8 of a supporting arm 9. Bowed plates 10 constitute members resiliently interposed between the shoulder 4 and the side 6 of the pane and between the arm portion 8 and the other side 11 of the pane. The intermediate portion 12 of each of the bowed members 10 bears against a respective side of the pane 1, one of the bowed members having its ends 13 bearing against the said shoulders 4 and the other bowed member having its ends 13 bearing against the arm portion 8, both ends 13 of each plate being bifurcated or recessed intermediately as at 14 to form branches or projections 15 which straddle the said tongues 3. The band 5 and plates 10 constitute pane-holding means.

The other end of the arm 9 preferably is also bent at a right angle to form a lateral projection 16, parallel to and preferably extended in a direction opposite to that in which the arm projection 8 extends. The extension 16 is pivotally received in a bearing 17 formed on a substantially U-shaped band 18 by curling one end of the latter. The band 18 is springy, and is attached to the upper side of the marginal frame 19 of a windshield 20 by mere pressure, the ends 17 and 21 spreading apart and resiliently clamping the bracket 18 thereto. There are preferably two supporting arms 9 and associated parts for each, each arm supporting a respective end of the pane 1.

The brackets 18 may be adjusted along the windshield frame, affording a simple means of varying the position of the glare shield laterally. The extensions 8 and 16 of the arm 9 rotate stiffly in their respective bearings, the friction therein being sufficient to prevent accidental displacement of the arms 9 and shield 1 from the position to which they have been adjusted. The pressure of the ends 13 of one of the plates 10 on the arm extension 8 increases the friction in the bearings 7. The shield 1 may be raised or lowered by reason of the swinging motion of the arms 9 in the bearings 17; and the inclination of the shield 1 may be varied by reason of the pivotal connection of the latter to the arms 9. Some of the alternative po-

sitions to which the device may be adjusted are indicated in dotted lines in Figure 2. It will be observed that all the adjustments may be made practically instantly by mere pressure alone in the direction of the desired adjustment; and the friction of the several bearings will maintain the shield in its adjusted position. It is also worthy of note that the shield may be readily detached 10 from its supporting or operating means by merely removing the arm extension 8 from the bearings 7, when the parts 5 and 10 may be easily removed, the extension 8 when in bearings 7 forming means for locking the 15 parts 5 and 10 into engagement with the shield 1. A pane of different tone or color may therefore be very easily substituted for the one in use should it be necessary or desirable to make such a change. For instance, in summer it may be preferable to 20 use a darker pane than in winter.

The bracket 18 forms a convenient attachment means applicable to a windshield frame; but is not so easily applied to a car 25 of the closed type. In order to be able to attach the device to the window frame of a closed car, the bracket 22 is preferably substituted for the bracket 18, as shown in Figure 7. The bracket 22 is preferably in the 30 form of a plate having its lower end curled to form the bearing 17, and having ears 23 extended from its opposite ends and apertured at 24 to accommodate screws 25 by means of which it is attached to the window 35 frame 26.

Having thus fully described this invention, I hereby reserve the benefit of all changes in form, arrangement, order, or use 40 of parts, as it is evident that many minor changes may be made therein without departing from the spirit of this invention or the scope of the following claims.

I claim:

1. The combination of an apertured pane, 45 a fastening element passing through the

said aperture and having a shoulder at one end and a recess at the other, a supporting arm for the pane passing through the said recess, and members resiliently interposed between the shoulder and one side of the 50 pane and between the arm and the other side of the pane respectively.

2. The combination of a pane having a pair of holes therein, a substantially U-shaped member having a pair of apertured tongues continuing one from each end thereof and passing through the said holes respectively, a supporting arm for the pane passing through the said apertures and means resiliently engaging the opposite sides 60 of the pane and borne by said member.

3. The combination of a pane having a pair of holes therein, a substantially U-shaped member having a pair of apertured tongues continuing one from each end thereof to form shoulders thereat and passing through the said holes respectively, a supporting arm for the pane passing through the said apertures, and bowed resilient members each bearing against a respective side 65 of the pane with its intermediate portion, one of the bowed members having its ends bearing against the said shoulders and the other bowed member having its ends bearing 70 against the said arm.

4. The combination of a pane having a pair of slits therein, a substantially U-shaped band having a pair of apertured tongues continuing one from each end thereof to form shoulders thereat and passing through the said slits respectively, a supporting arm for the pane passing through the said apertures, and bowed resilient plates each bearing against a respective side 80 of the pane with its intermediate portion and having bifurcated ends which straddle the said tongues.

In testimony whereof I hereunto affix my signature.

REAF F. WILLIAMS.
